UNITED STATES PATENT OFFICE.

WILLIAM GREEN, OF PORTLAND, OREGON.

SERVING-MACHINE.

1,382,502.

Specification of Letters Patent. Patented June 21, 1921.

Application filed May 15, 1920. Serial No. 381,767.

To all whom it may concern:

Be it known that I, WILLIAM GREEN, a citizen of the United States, residing at Portland, in the county of Multnomah and 5 State of Oregon, have invented new and useful Improvements in Serving-Machines, of which the following is a specification.

Because of exposure to the elements riggings of ships are covered with a fine rope, 10 wire, or hemp which is wound around the cable comprising the rigging. This rigging covering is usually applied by a serving mallet employed by one hand, while another hand manipulates the ball of marline so that 15 the operator of the serving mallet can turn the same with the marline around the rigging cable. The operation, as stated, requires the employment of two hands, the process is slow and tedious, and consequently 20 the application of the cover to the cable is both laborious and expensive.

The process of winding the outer covering on the rigging cable is referred to in the art as serving, and it is the object of the present 25 invention to produce a motor operated means which will effectively wind the outer covering, commonly referred to as marline, on a cable rigging in an easier, quicker and better manner than has heretofore been accomplished.

A further object is to produce a serving machine which shall be automatic in action, cheap in construction, efficient in operation and which will necessitate only the employment 30 of an unskilled hand for attending the motor and for applying the spool of new marline to the machine as the same is used.

It is a further object of the invention to produce an automatic serving machine for 35 the covering of ship riggings wherein the mechanism employed for winding the marline around the rigging cable may, by reverse operation, be also employed for supplying the machine with marline as the same 40 is used up.

The foregoing objects, and others which 45 will appear as the nature of the invention is better understood, may be accomplished by a construction, combination and operative 50 arrangement of parts, such as is illustrated by the drawings.

In the drawings:

Figure 1 is a side elevation illustrating the machine in operation.

Fig. 2 is a top plan view thereof. 55

Fig. 3 is an end elevation.

Fig. 4 is a sectional view approximately on the line 4—4 of Fig. 3.

Fig. 5 is a sectional view approximately on the line 5—5 of Fig. 1. 60

Fig. 6 is a sectional view approximately on the line 6—6 of Fig. 2.

Fig. 7 is a detail sectional view approximately on the line 7—7 of Fig. 4.

The cable 1 to be covered is arranged longitudinally in the room of the workshop in which the serving operation is accomplished. The cable is stretched tight and held taut by any suitable means, such for instance as block and tackles and suitable "horses" for 70 supporting the cable adjacent to the ends thereof.

The improved serving machine includes a frame that is mounted on wheels and casters for movement through the workroom longitudinally of the cable. 75

The frame is broadly indicated by the numeral 2, and has its lower corners at what I will refer to as the front of the machine provided with wheels 3 that have their 80 shafts journaled in suitable brackets 4 which are secured to the frame proper. The rear of the frame is also provided with brackets 5 that are arranged inward of the outer corners of the said frame, and these brackets 85 provide bearings for caster wheels 6. On the base 7 of the frame 2 there is mounted a motor 8. This motor may be of any desired or preferred type, that disclosed by the drawings being in the nature of a small electric motor which receives power from the source of electricity for lighting the workshop and for driving other machines therein. 90

The corner members of the frame are 95 preferably arranged at an inward angle with respect to the longitudinal plane of the same frame, and the said corner posts, at the upper ends thereof are connected by both cross beams 9 and longitudinal beams 100 10. The cross beams 9, at a suitable distance from the center of the frame have also

secured thereto longitudinal beams 11, and between the inner beams 11 and the outer beams 10 there are secured plates 12. This arrangement, it will be noted, provides an open space at the center of the top of the frame, and it is in a line with this space that the motor 8 is positioned.

On the plate 12, adjacent to the ends of the frame there are secured the angle leg portions 13 of elevation bearings 14. The members 14, as a matter of fact, comprise only the lower sections of bearings for a two-part hollow shaft which is broadly indicated by the numeral 15. The upper members of the bearings are indicated by the numeral 16 and are adjustably connected to the lower bearing members 14 by elements 17.

Each of the sections of the shaft 15 is semi-cylindrical in cross section, and are preferably hingedly connected together. These sections, however, are susceptible to adjustment with respect to each other so that cables 1 of varying thicknesses may be received through the bore of the shaft. The shaft is also arranged for free turning in its bearings.

On the end of the shaft at what I will term the rear of the frame there is a fly wheel 18. The means for securing this fly wheel, as well as the other elements which are attached to the shaft and which will herein-after be set forth in detail, are adjustable, being preferably in the nature of binding elements 19 so that the members which are associated with the shaft will be effectively sustained thereon regardless of the varying cross sectional diameters of the shaft incident to the different sizes of cables that pass therethrough. In a line with the belt wheel 20 on the power shaft of the motor 8 there is a pulley wheel 21 on the shaft 15, and around these wheels 20 and 21 there is trained an endless belt 22.

The motor is reversible so that the belt 22 may be turned in either of two directions.

On the shaft 15, at the front end of the frame, there are two spaced collars 24-24. These collars are sustained on the shaft by binding elements 25. Between the collars there is a spool 26 on which the marline or the wrapping rope or wire for the cable 28 is wound. On the outer collar 24 is a pipe or tube 29. This tube has its outer end rounded inwardly from the spool 26 and its inner end, on its outer face slotted, as at 30. The marline is passed through the tube and passed through the slot thereof, and is first wound around and preferably knotted on the cable. One of the sections of the shaft 15, at the front end of the device is projected over the end of the other section. Thus the wound cord or marline on the cable is received in the bore of the projecting section of the shaft. The cord or marline contact-

ing with the wall of the bore will be wound on the cable for only one thickness thereof.

The motor is operated to revolve the shaft in one direction. The marline will wind off of the spool on to the cable. The end twist 70 of the marline will contact with the outer collar 24. The tube which provides the guide arranges the marline so that it will be properly fed on to the cable. This contacting engagement with the end coil or twist of 75 the marline against the collar 24 will exert a pressure on said collar which is conveyed to the frame, causing the frame to be moved longitudinally on the cable as the marline is wound on the said cable. Thus the machine arranged at one end of the workroom will automatically serve to the opposite end thereof as long as there is marline on the spool. When the first supply of marline is exhausted the motor is halted. The end of 80 a new marline is secured on the spool and the motor is caused to turn the shaft 15 in the reverse direction. This again fills the spool. The shaft and frame are held against longitudinal movement by the operator during the filling of the marline on the spool. 90

The nature of the invention is such that the same is necessarily susceptible to various changes and modifications, and it is thought that the foregoing description exemplifying 95 the construction illustrated by the drawings will make clear to those skilled in the art to which this invention relates the operation and advantages thereof. The details of construction, etc., are to be limited only by the 100 scope of my claims.

Having thus described the invention, what I claim is:

1. In a serving machine, a wheeled frame, a hollow motor driven shaft thereon, a spool 105 of cord supported on the shaft, a tautly supported cable passing through the bore of the shaft, means for feeding a strand of cord from the spool to the cable to permit of the cord being wound around the cable as the 110 shaft is rotated, means carried by the shaft and overlying the wound cord on the cable for preventing the bunching of the cord on the cable, and means actuated by the cord in the winding thereof on the cable for moving 115 the frame longitudinally of the cable.

2. In a serving device, a wheeled frame, a sectional shaft journaled in bearings thereon, means for revolving the shaft, controlled 120 means for said first mentioned means, a spool removably supported on the shaft and carrying a cord, a taut supported cable passing through the shaft, a guide for the outer end strand of the cord for directing the same on to the cable to permit of the unwinding of the cord from the spool and the winding thereof on the cable when the shaft is revolved, and said cord, during the winding thereof on to the cable contacting with one end of the shaft and by virtue of the said 125 130

contact moving the shaft and frame longitudinally of the cable.

3. In a serving device, a wheeled frame, a removable sectional hollow shaft journaled thereon, and one of the sections of the said shaft extending beyond the end of the other section, motor drive means between the shaft and frame, and said shaft receiving a taut

supported cable therethrough, spaced collars on the shaft, a spool on the shafts between 10 the collars carrying a cord which is to be wound around the cable, and a hollow directing member for the end strand of the cord, as and for the purpose set forth.

In testimony whereof I affix my signature. 15
WILLIAM GREEN.
